UNITED STATES PATENT OFFICE.

ISHAM RANDOLPH, OF CHICAGO, ILLINOIS.

DETECTOR APPLIANCE FOR RAILWAY-SWITCHES.

SPECIFICATION forming part of Letters Patent No. 441,379, dated November 25, 1890.

Application filed July 22, 1890. Serial No. 359,518. (No model.)

To all whom it may concern:

Be it known that I, ISHAM RANDOLPH, a citizen of the United States, residing at Chicago, in the county of Cook and State of Illinois, have invented a new and useful Improvement in Detector Appliance for Railway-Switches, of which the following is a specification.

My invention relates to an improvement in the form of detector involving a bar applied to the rail adjoining a switch-rail to extend lengthwise along the same, and provided with mechanism for supporting it and adapting it to be moved vertically in performing its function of "detecting" or indicating the obstructed or clear condition of the track near the switch; and my invention relates particularly to improvement in the mechanism referred to for supporting the detector in a manner to permit it to be actuated for its purpose.

My improved detector appliance affords a very desirable device for use as such without any especial form of switch-operating appliance. I have particularly designed it, however, as part of a system of railway appliances other parts of which are described in Letters Patent No. 410,332, granted me on the 3d day of September, 1889, and No. 431,726, granted me on the 8th day of July, 1890.

In the accompanying drawings, Figure 1 is a representation of a railway-switch provided with my improved detector-bar appliance and showing my aforesaid patented devices as forming the means through the medium of which to operate it; Fig. 2, a section taken on the line 2 of Fig. 3 and viewed in the direction of the arrow; Fig. 3, a broken view in front elevation showing my improved appliance; and Figs. 4 and 5, sections taken, respectively, on the lines 4 and 5 of Fig. 3 and viewed in the direction of the arrows.

A is the rail to which the detector-bar B is applied. The means for supporting the bar B involve the following-described construction:

C is a clip for the inner side of the rail A, and D a bracket connected with the clip to extend at the outer side of the said rail and support the detector-bar B and the longitudinally-reciprocating detector-operating bar B', which is linked to the detector-bar in the man-

ner hereinafter described. The clip and bracket afford a support, and these supports are provided at desired intervals and in desired number on the rail A, as indicated at X in Fig. 1, and a detailed description of the construction thereof is as follows: The clip C involves two hook-arms, like the arm r' presented to view in Fig. 2, extending parallel with each other from one side of a plate r or base, provided on its opposite side near one end with a recess q or guide and near its opposite end with a bolt-hole p. The bracket D involves a plate o or base like that of the clip, (and both being preferably of the angular shape illustrated in Fig. 3,) and thus provided like the clip with a recess q' or guide and a bolt-hole p'. From a side of the base o (forming its outer side when in the operative position hereinafter described) extend the parallel upward-projecting arms n, each of which is bifurcated vertically from its upper end, affording a guide-recess m, Fig. 4, for the bar B' between the prongs l and k, the latter of which extends the higher and is expanded laterally toward its upper end into a guide-flange k'. The bracket and clip form a species of chair for the rail A by causing the arms r' of the clip to hook over the inner rail-flange, with the plate r to extend vertically underneath the base of the rail, and parallel therewith the plate o of the bracket D, which, as shown in Fig. 2, affords the seat for the outer rail-flange, the two plates r and o being adjustably secured together by a bolt p², passed through the bolt-holes p and p', and controlled for their adjustment by a spacing-block i, inserted between them into the guide-recesses q and q'. Thus the chair species of support may be adjusted to fit a rail A, having a narrower head to bring the detector-bar the closer to it by inserting the block i, of suitable width, to spread the plates r and o toward their lower edges and bring them the nearer together toward their upper edges. To spread the bases o and r toward their upper edges for controlling the position of the detector-bar with relation to a rail A, having a wider head, obviously the bolt p² should be first loosened and a narrower block i inserted. Between each pair of prongs l on the upper edge of the plate or base o extends a web h, preferably inclining upward from

each arm toward a central line between them forming the apex h' ; and between the said arms of each chair device the longitudinally-reciprocating operating-bar B' is linked to 5 the detector-bar B by a link B^2 , pivotally fastened near its upper end to the outer side of the detector-bar, and bifurcated toward its lower end to straddle the bar B' and house a roller g on a shaft g' , passed through the 10 prongs of the bifurcated end of the link, and also through the bar B' , the roller resting upon the guide-track afforded by the web h . To confine the bar B' in its seats at the bases of the recesses m of the bifurcated arms n , I 15 pass a key f through each pair of prongs l and k above the bar. Adjacent to the guide-flanges k' , forming the upper ends of the prongs l , and flanking them, are stops e , riveted to the outer side of the detector-bar B , 20 and provided along their inner edges with lips e' to overlap the flanges k' , between the edges of which and the stops e are seated anti-friction rollers (balls) d . (See Fig. 5.)

With the bracket and clip devices or supports applied in desired number and at desired intervals to the rail A , and supporting the detector-bar B and its operating-bar B' in the manner described and in their normal relative positions, as illustrated, the links B^2 30 all incline from their upper ends downward, thus with the rollers g at a lower end of the track h .

To operate the device to cause the bar B to perform its detecting function the bar B' is 35 moved longitudinally. This tends also to move similarly the detector B ; but the latter is obstructed by engagement of the stops e and guide-flanges k' , causing the links B^2 to tend toward a vertical position, thereby raising the bar B , the resistance to which in rising 40 is reduced to the minimum by the provision of the anti-friction balls d . By forming the tracks h of the inclining construction described, the links B^2 may be the shorter, (and 45 also, therefore, the stronger,) since the rise in the tracks increases the elevation of the detector-bar to the desired extent. When the bar B has been raised to its highest position by the rollers of the links B^2 reaching the 50 apexes h' on the tracks h , unless means be provided to hold or lock it there; as may be, the continued movement of the actuating-bar B' will carry the rollers over the apexes h' , and the weight of the parts will then suffice 55 to lower the detector-bar by forcing the rollers g down the tracks h toward their opposite ends, thereby relieving to that extent the operator of exertion. When then the detector-bar is again to be raised, the operation is obviously accomplished by moving the actuating-bar B' in the direction opposite that explained.

The details thus described as forming the construction of my improved device are believed to produce the best form of the appliance; but I do not wish to be understood as limiting myself thereto, as they may be vari-

ously modified, and parts thereof may even be omitted, without thereby departing from my invention.

A common manner of producing movement of the longitudinally-reciprocating actuating-bar B' is by controlling it from a lever located, say, in the operator's cabin or tower.

As hereinbefore stated, my improved detector-bar appliance is especially designed by me to be operated in conjunction with my aforesaid formerly patented appliances, which are shown in Fig. 1 of the drawings in the relative positions and to operate in the manner set forth in my said Patent No. 431,726. Thus when the operating-lever (not shown) is operated to pull the cable w in the direction indicated by the arrow in Fig. 1, before the switch is thrown by the eventually-resultant action of the appliance E , the lost motion of its longitudinally-movable bar v , (as also of the slotted links v' ,) and this, through the medium of its connection x with the cam-bar t of the appliance F , turns the lever t' of the latter in the direction to effect, through the links u and u' and intermediate pivotal bar u^2 , the desired movement of the bar B' , the device F serving when the rollers g of the links B^2 have reached the apexes h' of the tracks h to hold them there momentarily, (or longer, if desired,) owing to the locking effect of the stops t^2 on the cam-bar t by their being brought in the continued longitudinal movement of the cam-bar t against the straight edges of the latter, and thus to flank the two recesses t^3 at opposite sides of the tongue t^4 .

What I claim as new, and desire to secure by Letters Patent, is—

1. In a detector-bar appliance, the combination of a detector-bar B , a support for the detector-bar, comprising a chair for the base of the rail A , to which the bar B is applied, the said chair being formed with a combined clip and bracket, and a reciprocating actuating-bar B' , connected with the detector-bar and supported immediately by the bracket, substantially as described.

2. In a detector-bar appliance, the combination of a detector-bar B , a support for the detector-bar, comprising a chair for the base of the rail A , to which the bar B is applied, the said chair being formed with a combined relatively-adjustable clip and bracket, and a reciprocating actuating-bar B' , connected with the detector-bar and supported immediately by the bracket, substantially as described.

3. In a detector-bar appliance, the combination of a support comprising a combined clip C and bracket D , forming a chair for the rail A , the bracket having bifurcated arms n , forming guide-recesses m , and connected by a guide-track, a reciprocating actuating-bar B' in the recesses m , a detector-bar B , supported on the bar B' through the medium of a link B^2 , having a guide-roller g on the track, and suitable opposing-stops on the detector-bar, and arms n , substantially as described.

4. In a detector-bar appliance, the combination of a support comprising a combined clip C and bracket D, forming a chair for the rail A, the bracket having bifurcated arms n, 5 forming guide-recesses m, and connected by a guide-track h, rising from opposite ends toward an apex h', a reciprocating actuating-bar B', confined in the recesses m, a detector-bar B, supported on the bar B' through the 10 medium of a link B², having a guide-roller g on the track, and suitable opposing-stops on the detector-bar, and arms n, substantially as described.

5. In a detector-bar appliance, the combination, with the rail A, of a clip C, formed with a base r, having hook-arms r', a bracket D, having a base o, and adjustably connected with the base r below the said rail, bifurcated arms n, extending from the base o and provided with recesses m and stops k', a reciprocating actuating-bar B' in the recesses m, a link B², connected at its lower end with the bar B', a track h between the arms n, a roller g on the lower end of the link and resting on the track, and a detector-bar B; pivotally connected with the link near its upper end, and 25

provided with stops e, substantially as described.

6. In a detector-bar appliance, the combination, with a rail A, of a clip C, formed with a base r, having hook-arms r', a bracket D, having a base o, and connected with the base r below the said rail, a block i, confined between the said bases, arms n, extending from the base o and terminating in prongs l and k, 30 forming recesses m, stops k' on the prongs k, a reciprocating actuating-bar B' in the recesses m, a track h between the arms n, a link B², bifurcated toward its lower end and straddling and connected with the bar B', a 40 roller g in the bifurcated end of the link and resting on the track, a detector-bar B, pivotally connected with the link near its upper end, stops e on the detector-bar overlapping the stops k', and anti-friction rollers d, 45 confined between the stops, substantially as described.

ISHAM RANDOLPH.
